[57] CLAIM

The ornamental design for a novelty golf putter, as shown and described.

DESCRIPTION

FIG. 1 is a perspective view of a novelty golf putter showing my new design. The head is shaded to indicate transparency;

FIG. 2 is a top plan view thereof;

FIG. 3 is a side elevation thereof;

FIG. 4 is an end elevation taken from the right of FIG. 1;

FIG. 5 is an opposite end view from that of FIG. 4;

FIG. 6 is a reduced perspective view of the novelty golf putter but with a shortended shaft.

FIGS. 2 through 5 are shown fragmentarily for convenience of illustration.
